Inventor: John A. Sodestrom,

By Thomas G. Orwig, Attorney.

UNITED STATES PATENT OFFICE.

JOHN A. SODESTROM, OF SAC CITY, IOWA.

HAND-POWER BRICK-MACHINE.

No. 820,895.

Specification of Letters Patent.

Patented May 15, 1906.

Application filed November 22, 1904. Serial No. 233,901.

To all whom it may concern:

Be it known that I, JOHN A. SODESTROM, a citizen of the United States, residing at Sac City, in the county of Sac and State of Iowa, have invented a new and useful Hand-Power Brick-Machine, of which the following is a specification.

My object is to provide a machine adapted to be manually operated to make pressed building-brick from sand and cement or other suitable concrete material that requires no burning and that will harden and complete the brick as required for practical use by drying in the atmosphere.

15 A further object is to make parts of the machine adjustable for making brick of different width at different times.

20 My invention consists in the construction of elements and subcombinations and the arrangement and combinations of all the parts required to produce a complete operative machine, as hereinafter set forth, pointed out in my claims, and illustrated in the accompanying drawings, in which—

25 Figure 1 is a side elevation of the machine and shows the positions of the operative parts relative to each other and the frame with which they are connected, and also shows the lever in position as required to lower the plunger in the mold to its limit for admitting concrete to be filled into the mold. Fig. 2 is an enlarged vertical sectional view of Fig. 1 and shows the plunger in the fixed mold elevated to its limit in the mold, as required to 30 press a brick in the top of the mold. It also shows a modification in that the mold does not project above the top surface of the top of the machine. Fig. 3 is a detail view that shows an adjustable stop on the plunger for 35 restricting the upward passage of the plunger in the fixed mold, as required for lifting brick out of the mold when the stop is properly adjusted.

The numeral 10 designates the frame, that 40 is preferably made of iron and adapted to be fixed on a floor in a building or on a fixed base by means of bolts or in any suitable way. A cross-piece 12 is fixed to the lower portion 45 of the frame for supporting an open-ended mold 13, that is fixed to the top of uprights 14, fixed to the cross-piece to support the mold and also serve as bearers for the slide- 50 able plunger 15, fitted in the mold, as shown in Fig. 2. A cross-piece 16 at the top of the 55 frame also aids in supporting the mold 13,

that is fixed thereto in an upright position by means of screws or in any suitable way.

At one corner of the frame there are two parallel uprights to which a lever 17 is connected by means of bearers *a*, adjustably 60 fixed to the parallel uprights of the frame by means of bolts 19, extended through bores in the uprights and slots in the bearers in such a manner that the lever can be raised and lowered relative to the fixed mold 13, as required 65 for making brick of different widths at different times.

To connect the short arm of the lever 17 with the mold, as required to force the plunger 15 up into the mold to compress concrete 70 in the mold to produce a pressed brick, a metal link 18, that has a hook at each end, is hung upon the lever and its lower end slipped over the bottom of the plunger, that is provided with a notch to admit the hook at the 75 lower end of the link.

To lift the plunger 15, as required to lift the brick out of the mold, a longer link 19, provided with a hook on its end, is also connected with the lever 17 to engage the plunger 80 at its lower end to transmit power to the plunger.

To regulate the distance of the upward passage of the plunger 15 in the mold, a stop 20 is adjustably connected to the face of the 85 plunger, as shown in Fig. 3, or in any suitable way.

When brick of greater width are to be made, the lever 17 must be adjusted by lowering the adjustable bearings *a* on the frame 90 10, so the plunger 15 can be dropped lower by means of the links 18 and 19.

To pull down the plunger 15 to its limit, a detent 21 is adjustably attached to the end portion of the hook on the lower end of the 95 link 19.

To limit the upward motion of the plunger at different times, the detent 21 is raised or lowered on the link 19.

In Fig. 2 the mold 13 is shown to be made 100 of wood and lined with metal plates. It is obvious it may be all metal.

A removable top 22 is placed on the top of the frame to extend outward relative to the frame for placing concrete thereon and receiving brick as they are pushed up out of the mold.

To close the top of the mold, a post 23 is fixed to the frame and a straight bar 24, preferably hard wood, is hinged to the lower end 110

of the post to extend over the top of the mold and a metal plate 25 fixed to its under side to overlie the open top of the mold, and a latch 26 is hinged to the free end of the bar 5 24 and will engage a striker 27, fixed to the top of the frame 10, as required to lock the bar and plate 25 on top of the mold, as shown in Fig. 1.

A spring 28, fixed to the bar and the top of 10 the post, normally retains the bar elevated and out of the way while concrete is being filled into the mold.

It is obvious the face of the plate 25 may 15 be serrated or provided with designs of various forms for producing figures or ornamental faces on the brick produced by pressing them against the face of the plate.

In the practical operation of my machine 20 plastic concrete is placed on the top and the plunger lowered to its limit by raising the long arm of the lever, and the mold then filled with concrete and the concrete scraped off evenly with the top of the mold and the bar that causes the plate to close the top of the 25 mold lowered and locked to the frame by means of the latch hinged to the bar. The long arm of the lever is then pressed down as required to complete the pressure of the concrete to form a finished brick by means of the 30 link 18, and when the brick is thus finished in the mold and the mold-top unlocked a further depression of the long arm of the lever will, by means of the link 19, elevate the plunger as required to push the finished brick 35 out of the top of the mold. A plate 29 is fixed on the short arm of the lever to retain the links 18 and 19 in place on the lever.

It is obvious the machine and mold may 40 vary in size as required to make brick of different length, widths, and thickness.

Having thus set forth the purpose of my invention and the construction and function of each element and subcombination therein, the practical operation and utility thereof 45 will be readily understood by persons familiar with the art to which it pertains.

What I claim as new, and desire to secure by Letters Patent, is—

1. In a brick-machine, a frame having two 50 uprights in parallel position and near to each other, adjustable bearings fixed to the uprights, a lever fulcrumed to said bearings, an open-ended mold fixed to the frame at the side of the lever, a plunger fitted in the mold 55 and means for adjustably connecting the short arm of the lever with the plunger, to operate as set forth.

2. In a brick-machine, a frame having two 60 uprights in parallel position and near each other, bearings provided with longitudinal slots and bolts passed through bores in the uprights and through the slots to clamp the bearings to the uprights, a lever fulcrumed to said bearings, an open-ended mold fixed to

the frame in upright position, a plunger fitted in the mold, links differing in length for connecting the short arm of the lever with the plunger, to operate as set forth. 65

3. In a brick-machine, a frame, an open-ended mold fixed to the frame, bearings for a 70 plunger extended downward from the mold, a platform at the top of the mold, a plunger fitted to the bearings and a lever fulcrumed to the frame in adjustable bearings fixed to the frame, a link having a hook at each end 75 connected at its top with the lever and at its bottom with the lower end of the plunger, to operate in the manner set forth.

4. In a brick-machine, a frame, an open-ended mold fixed to the frame, bearings for a 80 plunger extended downward from the mold, a plunger fitted to the bearings, a lever adjustably fulcrumed to the frame, a link having a hook at each end connected at its top with the lever and at its bottom with the 85 lower end of the plunger, a second link having hooks at its ends connected with the lever to engage the bottom of the plunger, to operate in the manner set forth.

5. In a brick-machine, an open-ended mold 90 fixed to the frame, a plunger fitted in the frame, a stop adjustably connected with the plunger, a link having a hook on its lower end to engage the lower end of the plunger, a detent adjustably connected with the end of 95 the hook and means for raising and lowering the link and plunger for the purposes stated.

6. In a brick-machine, a frame having two uprights in parallel position and near each other, adjustable bearings fixed to the uprights, a lever fulcrumed to said bearings, an open-ended mold fixed to the frame aside of the short arm of the lever, a plunger fitted in the mold, means for adjustably connecting the short arm of the lever with the lower end 100 of the plunger, a cover for closing the mold and means for locking the cover, arranged and combined to operate as set forth. 105

7. A brick-machine, comprising a frame, an open-ended mold fixed to the frame, bearings for a plunger connected with the lower end of the mold, a plunger fitted in the mold, a lever fulcrumed to the frame in adjustable bearings fixed to the frame, two links of unequal length having hooks at their lower ends 115 connected with the short arm of the lever to engage the lower end of the plunger, a stop device adjustably fixed to the plunger, a detent fixed to the hook portion of the longest link, a bar hinged to the top of the frame, a striker fixed to the frame and a latch hinged to the end of the hinged bar, arranged and combined to operate in the manner set forth for the purposes stated. 120
